UNITED STATES PATENT OFFICE.

GEORGE E. A. HALLETT, OF DAYTON, OHIO.

GAS MIXER.

Application filed March 28, 1921. Serial No. 456,283.

To all whom it may concern:

Be it known that I, GEORGE E. A. HALLETT, a citizen of the United States, residing at Dayton, in the county of Montgomery and State of Ohio, have invented certain new and useful Improvements in Gas Mixers, of which the following is a specification.

This invention relates in general to charge forming devices for internal combustion engines and more particularly to a mixing chamber wherein the fuel, as delivered from the carburetor, may be more thoroughly and intimately mixed. This invention further provides for the separation of any particles of liquid fuel, which may be carried over by the rush of gases, from the mixture, with the subsequent return of such particles to such a point in the intake manifold as will provide for their revolatilization.

Considerable difficulty has been experienced in internal combustion engines, particularly where low grade fuels are to be used, by reason of the incomplete volatilization of the liquid fuel delivered by the carburetor to the engine. It is well known that in high speed engines particularly, raw liquid fuel in large drops is drawn along the sides of the intake manifold and into the engine with the consequent improper mixture, waste of fuel and engine inefficiency and carbonization.

Furthermore, it has been noted that in high speed engines there are violent pulsations in the flow of the fuel mixture due to the intermittent rush of gases in the intake manifold incident to the opening and closing of the intake valves. These pulsations are sufficiently violent at high speeds to cause a certain amount of alternate carburetor flooding and engine starving. The fire risk incident to the said flooding is naturally very great and should be avoided. The unevenness of fuel feed due to the rebound of the gases upon the closing of the valve results in a temporary starving of the cylinder feed by the next inlet valve to open and results in extreme roughness in the operation of the motor.

It is the purpose of my invention to provide a mixing chamber with a fan or other means which will insure that the fuel components shall be thoroughly and intimately mixed.

A second object of my invention is to

adapt this mixing chamber to prevent any particles of raw liquid fuel from being drawn into the engine cylinders. By this provision a dry mixture will be insured.

A further object of my invention is to provide a means whereby the pressure at which the fuel is to be admitted to the cylinders may be regulated.

Another object of my invention is to provide means whereby the pulsations in the intake manifold caused by the intermittent opening and closing of the valves may be "damped" out.

While I do not limit the scope of my invention to the specific embodiment shown, it is believed that a full and complete disclosure of my invention may be found in the accompanying specification and drawings, in which—

Fig. 1 is a side elevation of my device as applied to an internal combustion engine;

Fig. 2 is a vertical section of the mixing chamber and intake manifold;

Fig. 3 is a section on the line A—A of Fig. 2;

Fig. 4 shows a modification of my mixing chamber as applied to an internal combustion engine; and

Fig. 5 is a section on the line B—B of Fig. 2.

Referring in detail to the drawings, my invention comprises a mixing chamber A and a centrifugal fan E centrally mounted therein. Mixing chamber A comprises two concentric compartments B and C, which are separated from each other by an upstanding web or flange 1. A removable plate 2 forms a closure for said casing. This plate is adapted to be removable to allow for the insertion of the fan E and is provided with a flange portion 3 which cooperates with the flange 4 of the casing A and with the bolt 5 and gasket 6 to form an air tight union with said casing. Closure plate 2 is provided with a centrally disposed flanged opening as at 7 for the reception of an intake pipe 8 leading from the usual carburetor outlet pipe 9. The closure plate may be attached by screw threads or any other known means to the manifold pipe. The compartments B and C of the main casing communicate with each other through openings 10 which are provided by short sections of pipe 11 which shall be hereinafter termed outlet members 110

and which are fixed in the web or flange 1 in such a manner that the walls of said pipe extend well into the interior of the casing B and at least slightly into the interior of the casing C. The purpose of such an arrangement of the pipes 11 will be hereinafter described. The back plate 12 of the casing A is provided with a centrally located flange portion 13 having a bore 14 at the center of the casing for the reception of a shaft 15 on which the fan E is mounted. A key 16 and a bolt 17 are provided to hold the fan E rigidly on the shaft 15. This flange portion is further provided with a recess 18 for the reception of an idling shaft 19 which forms a part of the fan propelling means, as will be described in detail hereinafter.

At the lowermost portion of the compartment B there is provided an outlet 20 to permit the drainage of liquid particles into the compartment C and through the opening 21 at the lowest part of the compartment C through the pipe 22 and into a point of the intake manifold 8 adjacent to the carburetor outlet. Drainage pipe 22 is secured to the intake manifold and to the mixing chamber by the usual taps and nipples. The casing A is provided at its uppermost portion with a flanged outlet opening 23 which is adapted to be fastened to a correspondingly flanged portion of an intake manifold pipe 25. The fan in this mixing chamber may be designed to be propelled in any given manner but in this preferred embodiment it is shown as being operable by a fluid actuated turbine, and as particularly shown in this modification is to be operated by the oil in the oil circulating system of the engine.

A casing 26 is provided for the fan propelling means. This casing is adapted, as shown, to be bolted or otherwise secured to the flanged portion 13 of the casing A. This casing provides two bearings 27 and 28 for the reception of the working shaft 15 and the idling shaft 19, respectively. A gear 30 is keyed to the shaft 15 by means of a key 29. A second gear 31, so adapted that its teeth will mesh with those of the gear 29, is mounted on the shaft 19 and keyed thereto by a key 32. A baffle plate 33 is provided which extends substantially the full width of the casing 26 leaving only a small channel 34 at each side thereof. A pipe 35 is shown as the inlet from the oil circulating system to the casing 26 while the pipe 36 shows the outlet from said casing to the oil circulating system.

The operation of this fan propelling means will then be seen to be as follows:

The oil entering through the pipe 35, under pressure, will strike the baffle plate 33 and passing to the side of the casing through the narrow channel 34 will impel the upper

gear, as viewed in Fig. 5, in a counter-clockwise direction and the lower gear in a clockwise direction. The gear 31 by meshing with the gear 30 assists in rotating the fan E. It is proposed that a means shall be provided for governing the pressure at which the oil is admitted to the casing 26 so that the speed of rotation of the gears, and consequently the fan, may be thereby regulated.

From the foregoing the operation of my device will be seen to be as follows:

The explosive mixture leaves the carburetor outlet 9 and passing through the intake manifold 8 will be admitted centrally of the casing A through the opening in the front closure plate 2. There it will immediately be received by the fan which will whirl the gas particles violently centrifugally against the web 1 and out through the openings 10 into the outer annular compartment C. It will be noted that the openings 10 are equidistantly disposed around the casing B and are so arranged that none of the gases shall be thrown by the direction of the fan directly through the outlet passage defined at 23. Any particles of raw liquid fuel which may be carried along the intake manifold by the sweep of the explosive gases will be thrown violently against the web 1 and to a certain extent broken up into finer particles or volatilized. Any unvolatilized particles of liquid fuel, however, will be drawn along the sides of this compartment B and through the outlet 20 and the drain pipe 22 back into the lower portion of the intake manifold 8 whereby they will again strike the incoming gases and have an opportunity to be revolatilized.

The pipes 11, providing for the communication between the two chambers B and C, will, by reason of the fact that their walls extend well into the casing B, prevent any of these liquid particles from being drawn outwardly into the annular casing C. It will thus be seen that I have provided a mixing chamber which will insure a complete mixing of the fuel components and which will provide for the drying of the mixture by excluding therefrom any particles of raw liquid fuel.

If it is desired, as in the case of internal combustion engines operating at changing altitudes, to vary the pressure at which the fuel mixture is to be delivered to the engine, this can be accomplished by increasing the rate of revolution of the fan. This, as previously stated, can be controlled by any suitable governing means.

It will be noted that the casing which I have described will provide for the damping out of the pulsations.

It will be noted that by means of my device the intake manifold vacuum may be increased at will with the consequent regulation of fuel supplied from the carburetor.

A very important feature of my invention is the ease and simplicity of installation of my device. The fan casing is adapted to be readily installed between the carburetor and the usual intake manifold outlet. The motor for actuating this fan is of exceedingly simple construction and easily assembled on the casing. The fact that the fan motor is fluid operated prevents the complications incident to supplying a system of gears or other mechanical transmission.

With the modification shown in Fig. 4, I have dispensed with the outer compartment C and proposed to lead the mixture from the compartment B directly to the cylinders. As shown in this modification, there is provided a separate intake manifold for each cylinder, all of which are of equal length and extend into compartment B at equally disposed points. The ends of these individual intake manifold pipes are to extend well into the casing in exactly the same manner as the communicating pipes shown in Fig. 3.

I claim:

1. In a fuel mixing device for use in internal combustion engines, a casing adapted to be mounted between the carburetor and the engine intake manifold, said casing comprising a mixing chamber having a centrally disposed inlet and a plurality of circumferentially disposed outlet members, and a positively operated centrifugal fan mounted in said mixing chamber.
2. In a fuel mixing device for use in internal combustion engines, a casing adapted to be mounted between the carburetor and the engine intake manifold, said casing comprising a mixing chamber having a centrally disposed inlet and a plurality of circumferentially disposed outlet members, the walls of said outlet members extending to a point inwardly of the chamber walls for the purpose described, and a positively operated centrifugal fan centrally mounted in said mixing chamber.
3. In a fuel mixing device for use in internal combustion engines, a casing adapted to be mounted between the carburetor and the engine intake manifold, said casing comprising a mixing chamber having a centrally disposed inlet and a plurality of circumferentially disposed outlet members, the walls of said outlet members extending to a point inwardly of the chamber walls for the purpose described, an annular outlet casing mounted concentrically of the mixing chamber and adapted to receive the fuel mixture from said mixing chamber through said outlet members, a positively operated centrifugal fan centrally mounted in said mixing chamber, and an outlet from said annular outlet casing so disposed as to be out of the direct line of flow of the gases passing through the outlet members.
4. In a fuel mixing device for use in internal combustion engines, a casing adapted to be mounted between the carburetor and the engine intake manifold, said casing comprising a mixing chamber having a centrally disposed inlet and a plurality of circumferentially disposed outlet members, the walls of said outlet members extending to a point inwardly of the chamber walls for the purpose described, an annular outlet casing integral with and mounted concentrically of the mixing chamber and adapted to receive the fuel mixture from said mixing chamber through said outlet members, and a positively operated centrifugal fan centrally mounted in said mixing chamber.
5. In a fuel mixing device for use in internal combustion engines, a casing adapted to be mounted between the carburetor and the engine intake manifold, said casing comprising a mixing chamber having a centrally disposed inlet and a plurality of circumferentially disposed outlet members, the walls of said outlet members extending to a point inwardly of the chamber walls for the purpose described, an annular outlet casing mounted concentrically of the mixing chamber and adapted to receive the fuel mixture from said mixing chamber through said outlet members, a positively operated centrifugal fan centrally mounted in said mixing chamber, and an outlet from said annular outlet casing so disposed as to be out of the direct line of flow of the gases passing through the outlet members.
6. In a fuel mixing device for use in internal combustion engines, a casing adapted to be mounted between the carburetor and the engine intake manifold, said casing comprising a mixing chamber having a centrally disposed inlet and a plurality of circumferentially disposed outlet members, the walls of said outlet members extending to a point inwardly of the chamber walls for the purpose described, an annular outlet casing integral with and mounted concentrically of the mixing chamber and adapted to receive the fuel mixture from said mixing chamber through said outlet members, a positively operated centrifugal fan centrally mounted in said mixing chamber, and an outlet from said annular outlet casing so disposed as to be out of the direct line of flow of the gases passing through the outlet members.

In testimony whereof I have affixed my signature.

GEORGE E. A. HALLETT.
